UNITED STATES PATENT OFFICE.

WILLIAM A. GRIBBLE, OF COLLINSVILLE, TEXAS.

ACETYLENE-GAS GENERATOR.

SPECIFICATION forming part of Letters Patent No. 783,947, dated February 28, 1905.

Application filed June 14, 1904. Serial No. 212,539.

To all whom it may concern:

Be it known that I, WILLIAM A. GRIBBLE, a citizen of the United States, residing at Collinsville, in the county of Grayson and State 5 of Texas, have invented certain new and useful Improvements in Acetylene-Gas Generators, of which the following is a specification.

The object of my invention is to provide a novel construction of gas-generating machine 10 which is composed primarily of a single main receptacle having a generating-chamber, carbid-holder, valve mechanism controlling the feed of the carbid to the generating-chamber, and a gas-bell mounted upon the generator and 15 connected with the valve mechanism aforesaid for operation thereof. The gas-space of the generating-chamber communicates with the gas-space of the gas-bell directly, and because of the arrangement of the generator with reference to the carbid-holder and bell the whole 20 machine is made in very compact form.

The invention obviates the necessity of use 25 of a generator and a separate gasometer having numerous intermediate connections and gas-controlling means, thereby greatly cheapening the cost of the generator and increasing the general desirability of my structure.

For a full description of the invention and the merits thereof and also to acquire a knowledge 30 of the details of construction of the means for effecting the result reference is to be had to the following description and accompanying drawings.

While the essential and characteristic features 35 of the invention are susceptible of modification, still the preferred embodiment of the invention is illustrated in the accompanying drawings, in which—

Figure 1 is a vertical sectional view of a 40 gas-generating machine embodying my invention. Fig. 2 is a horizontal section on the line X X of Fig. 1. Fig. 3 is a horizontal section on the line Y Y of Fig. 1.

Corresponding and like parts are referred 45 to in the following description and indicated in all the views of the drawings by the same reference characters.

Describing and designating the essential features 50 of my invention structurally, my machine comprises principally a generator 1,

which consists of a tank of suitable size governed chiefly by the amount of gas to be produced by the machine, and the carbid-holder 2 is disposed at the upper portion of the generator. The generator 1 is designed to receive 55 water, within which the carbid is projected upon operation of the valve mechanism, and at the upper end of the generator-receptacle 1 and surrounding same, preferably, is located the gas-bell 3. The upper end of the generator 60 1 is reduced diametrically, and the reduced portion, which is indicated at 1^a, is received within the gas-bell 3, as clearly shown in Fig. 1. The upper end of the generator 1 is open, so that the gas-space within the generator directly 65 communicates with the gas-space of the bell 3, and the decrease and increase of the gas-pressure within the generator will induce the necessary responsive action of the bell and operation of the valve mechanism operated by 70 said bell and by which the feed of carbid is regulated.

The carbid-receptacle 2 is of a suitable form for the purpose of the invention, being somewhat cone-shaped at its lower end, as 75 shown at 2^a, so that the carbid will feed regularly and to prevent formation of dead space within which the carbid might accumulate. Within the holder 2 is disposed a casing 4, closed at its upper end, and the valve 5 operates 80 within the casing, being movable toward and from a seat 6 adjacent the opening 7 in the lower end of the carbid-holder 2. The valve 5 is protected by the casing 4 from the carbid within the holder, said casing being disposed 85 slightly above the lower end of the holder and supported by suitable supports or wings 8, resting upon the portion 2^a of the carbid-receptacle. The valve 5 is operated directly by a rod 9, connected at its lower end to one 90 end of a pivoted lever 10, and a second valve-rod 11 connects the other end of the lever 10 with the gas-bell 3. The upper end of the rod 11 is the part thereof which is actuated by the bell 3, said rod 11 passing through a guide member, 95 (indicated at 12.) The valve-rod 11 is guided in its vertical movement by a guide-tube 13, and in order that the vertical movement of the gas-bell 3 may be uniform and to prevent binding of the bell in such movement a guide- 100

bar 14 is projected upwardly from the generator at a point approximately opposite to that part of the generator adjacent which the rod 11 moves, said guide-bar 14 passing 5 through a second guide member 15, extending laterally from the upper portion of the bell 3. Upon the reduced upper end 1^a of the generator 1 and surrounding said portion in spaced relation thereto is a shell 16, which 10 forms an annular chamber around the generator, said chamber receiving a liquid to form the necessary liquid seal between the bell 3 and the generator. A guide-tube 13 is attached to the outer portion of the shell, 15 above described. The location of the shell 16 is such that the compactness of the arrangement of the parts of the machine is promoted.

The lever 10 within the generator 1 is pivoted to a horizontal service-pipe 17, which is 20 located transversely of the lower portion of the generator, said service-pipe being provided with a vertical support 18, to which the lever 10 is directly fulcrumed. The service-pipe 17 extends out of the generator to any 25 suitable point. The vertical supply-pipe 19 extends upwardly from the portion of the service-pipe 17 disposed within the generator, the upper end of the said pipe 19 being projected into the gas-space within the generator.

30 Suitable caps 20 and 21 are provided upon the bell 3 and the carbid-holder 2, respectively, and these caps may be removed or replaced for obvious purposes. Lugs 22 or other suitable means may be projected from the 35 upper portion of the carbid-holder to support same in the upper portion of the generator.

The vertical stand-pipe 27 is shown in dotted lines in Fig. 1, and this pipe may be of any suitable form, being preferably adapted 40 to turn down in order to draw off the residuum which may have collected in the bottom of the generator. The lower end of the stand-pipe 27 is connected with the lower end of the generator by any suitable coupling. The 45 service-pipe 17 is provided in its length with a drier 28, which may be of any suitable type commonly used for this purpose, and a drip-receptacle 29 is connected with the lower end of the drier 28.

50 In order to set up and agitate the residuum in the generator preparatory to drawing off of the same, an agitating-arm 23 is disposed horizontally in the lower portion of the generator and said arm is actuated by means of a 55 vertical rod 24, projecting upwardly therefrom. The vertical rod 24 passes through the guide-tube 13 and is provided at its upper end with a handle 25.

A cotter-pin 26 is provided adjacent the 60 upper end of the valve-rod 11, and this pin is

adapted to be engaged by the adjacent guide member 12 in the downward movement of the bell 3. The engagement of the member 12 with the cotter-pin actuates the rod 11 so as to open the valve 5 to thereby admit of passage of the carbid from the holder 2 into the generator 1.

In its practical operation the variation in pressure of the gas within the generator 1 effects the operation of the gas-bell 3, reduction of such pressure causing the said bell to lower, and this movement effects engagement of the guide member 12 with the cotter-pin 26, thus causing the valve 5 to move away from its seat. Carbid is thus fed into the 75 generator-chamber and the increase of pressure in said generator raises the gas-bell and the member 12 moves out of engagement with the cotter-pin, thereby shutting off the flow of carbid due to seating of the valve 5. 80

Having thus described the invention, what is claimed as new is—

In an acetylene-gas generator, the combination of a generator having its upper portion reduced, a shell surrounding the upper portion of the generator and forming a liquid-chamber, a bell having its lower end received in the liquid-chamber aforesaid, a carbid-holder mounted in the upper portion of the generator, a valve controlling the feed of carbid from said holder, a service-pipe disposed transversely in the lower portion of the generator, a vertical supply-pipe leading from the gas-space of the generator into the service-pipe, a lever pivoted to the horizontal service-pipe in the generator, a rod connecting one end of the lever with the valve, a second rod connected at its lower end with the other end of the lever and having its upper end projected out of the generator alongside of the gas-bell, 100 a guide-tube secured to the shell aforesaid and receiving the valve-rod adjacent the bell, a guide-bar projected upwardly from the generator at the side opposite that upon which the last-mentioned valve-rod is disposed, guide 105 members projected laterally from the upper portion of the bell and coöperating with the guide-bar and last-mentioned valve-rod to direct the movement of the bell, and a pin extended from the upper end portion of the last-mentioned valve-rod and adapted to be engaged by the adjacent guide member of the bell to effect actuation of the valve. 110

In testimony whereof I affix my signature in presence of two witnesses.
